Filed Apr. 29, 1968, Ser. No. 11,676

Term of patent 14 years

Int. Cl. D7—04

U.S. Cl. D81—10

FIG. 3.

FIG. 1 is a side elevational view showing my new design for a combination table-cart and barbecue grill, the opposite side being a mirror image of the illustrated side;

FIG. 2 is a top plan view of my new design of the barbecue cart of FIG. 1; and

FIG. 3 is a front elevational view of my new design, the back elevational view being similar except for the size of the wheels and the presence of the steering bar or handle.

I claim:

The ornamental design for a combination table-cart and barbecue grill, substantially as shown and described.
